(57) **CLAIM**

The ornamental design for a 3D printer as shown and described.

DESCRIPTION

1.1 : Front

1.2 : Back

1.3 : Left

1.4 : Right

1.5 : Top

1.6 : Bottom

1.7 : Perspective

1.8 : Perspective

A new, original and ornamental design for a 3D printer, of which the following is a specification, reference being made to the accompanying drawing, forming a part hereof; **1.1** is a front view of a 3D printer, showing our new design; **1.2** is a back view thereof; **1.3** is a left side view thereof; **1.4** is a right side view thereof; **1.5** is a top view thereof; **1.6** is a bottom view thereof; **1.7** is a perspective view thereof; and **1.8** is another perspective view thereof; the portions illustrated by solid lines are the portions for which the claimed

(Continued)

design is intended; the broken lines in the drawings represent environment that form no part of the claim.

1 Claim, 8 Drawing Sheets
